ATTORNEY

UNITED STATES PATENT OFFICE.

JACOB NOTKIN, OF ROXBURY, MASSACHUSETTS.

DESIGN FOR AN ARTICLE OF PASTRY.

Application filed June 11, 1928. Serial No. 27,078. Term of patent 7 years.

To all whom it may concern:

Be it known that I, JACOB NOTKIN, a citizen of the United States, residing at Roxbury, in the county of Suffolk and State of Massachusetts, have invented a new, original, and ornamental Design for an Article of Pastry, of which the following is a specification, reference being had to the accompanying drawing, forming part hereof.

I claim:

The ornamental design for an article of pastry substantially as shown.

JACOB NOTKIN.
